DESIGN FOR AN AIR RETARDER FOR AN AUTOMOBILE RADIATOR

Theodore Arthur Brown, Council Bluffs, Iowa

Application November 30, 1936, Serial No. 66,200

Term of patent 3½ years

To all whom it may concern:

Be it known that I, Theodore A. Brown, a citizen of the United States, residing at Council Bluffs, in the county of Pottawattamie and State of Iowa, have invented a new, original, and ornamental Design for an Air Retarder for an Automobile Radiator, of which the following is a specification, reference being had to the accompanying drawing, forming a part thereof.

The air retarder of my design, shown in front elevation in the drawing figure, is adapted to fit on the right front portion of an automobile radiator.

I claim:

The ornamental design for an air retarder for an automobile radiator, as shown and described.

THEODORE ARTHUR BROWN.
